UNITED STATES PATENT OFFICE.

EDMOND ROSENBERG AND EDGAR W. MIX, OF PARIS, FRANCE, ASSIGNORS TO GENERAL ELECTRIC COMPANY, A CORPORATION OF NEW YORK.

POWER-GENERATING SYSTEM.

No. 905,752.

Specification of Letters Patent.

Patented Dec. 1, 1908.

Application filed April 23, 1907. Serial No. 369,841.

To all whom it may concern:

Be it known that we, EDMOND ROSENBERG, a citizen of the French Republic, and EDGAR W. MIX, a citizen of the United States, residing at Paris, France, have invented certain new and useful Improvements in Power-Generating Systems, of which the following is a specification.

The present invention relates to power-generating systems wherein high-pressure reciprocating engines exhaust into low-pressure turbines.

Our invention has for its object to provide an improved power-generating system of the character above referred to.

In carrying out the invention a low-pressure turbine is provided having suitable wheel buckets and nozzles or other fluid-discharging devices. Mounted on the main shaft of the turbine is the revolving element of an electric generator. In addition to this a fly-wheel of suitable dimensions is mounted on the main shaft so that, as the supply of steam decreases or increases with respect to the normal or the load changes, it will oppose the tendency of the turbine and generator to change speed. There will be a certain speed variation in such a combination but the amount thereof can be reduced to small limits by the judicious selection of the fly-wheel. Preferably the fly-wheel is located in that portion of the turbine casing containing a vacuum created by the condenser so as to reduce rotation losses.

Instead of providing a fly-wheel separate in itself, we may add to the bucket wheels or other rotating parts, over and above the mass required for structural reasons, the equivalent in weight of the fly-wheel. The use of a fly-wheel in the manner described enables us to do away with steam accumulators which are sometimes used with turbines utilizing the intermittent exhaust of reciprocating engines.

Where it is desired to have the generator supply current to a given load at constant potential, an automatic regulator is employed, which may be arranged to operate in any well known manner. For example, when the speed increases the regulator may be arranged to increase the resistance in the field circuit, and upon a decrease in speed the regulator may reduce the amount of resistance in circuit. The regulator may act in response to a centrifugal governor, or to a

change in potential on the mains of the generator. In the case of a direct-current generator the regulator may be employed to shift the brushes.

The speed of a low-pressure turbine supplied by the exhaust from a high pressure engine will with a fixed number of nozzles in service tend to vary with changes in the pressure and amount of said exhaust from a certain minimum to a certain maximum. Where the regulation of the speed of the turbine is not so important, as for example where a voltage regulator is employed the number of nozzles in service will correspond to the mean delivery. Where closer regulation is required the number of discharging devices in service may be controlled by pressure-actuated means or by a speed-responsive device. As an alternative construction we may govern the turbine by means of a throttle valve responding to speed or pressure variations. It will usually be simpler and more satisfactory to have a means connected with the primary or high-pressure engine govern the low-pressure engine or turbine. We may use a voltage or other form of electric regulator in combination with a valve mechanism for the turbine if desired.

Assume for example that the reciprocating engine is employed to drive the winding drum of a hoist in a mine. As the cage is moved from one level to another, stopping at each, the steam consumption will rise and fall as the cage is moved or held stationary. In order that the proper number of nozzle passages or other discharging devices in the low-pressure turbine may be opened and closed to accommodate the exhaust from the engine, the controlling mechanism therefor can be actuated by the same lever that moves the engine throttle valve. This action may take place through the medium of electricity, elastic fluid, liquid or mechanical means, as desired. Other means for governing the turbine by the cable-winding mechanism of the cage will readily suggest themselves. For example, the indicator showing the position of the cage in the mine shaft may be arranged to control the area of the admission ports of the turbine as it moves from place to place.

It is evident that a prolonged stop of the engine would result in the turbine stopping for the want of steam. To provide

against such a condition, the turbine may be specially constructed with a portion arranged to receive high-pressure steam from a boiler, and a portion to receive low-pressure steam from the engine. When the low-pressure portion only is in operation, the high-pressure portion is connected to the condenser so that the parts will rotate in a vacuum and the losses will be correspondingly small. Moreover, when only one portion of the turbine is receiving steam, the remainder is acting as a fly-wheel.

In the accompanying drawings, which illustrate one of the embodiments of the invention, Figure 1 is a diagrammatic view showing a reciprocating engine exhausting into a low-pressure turbine; and Fig. 2 is a longitudinal section of a combined high and low-pressure turbine built in accordance 20 with our invention.

1 represents a high-pressure reciprocating engine having the usual piston-rod and crank connection with the main shaft 2. Mounted on the latter is a fly-wheel 3 and 25 a winding drum 4, over which the cable 5 is wound. This cable is, or may be employed to raise and lower the cage of a mine hoist. The reciprocating engine is controlled by the throttle valve and lever 6. The exhaust 30 from the engine is supplied to the low-pressure turbine 7 by the conduit 8. This conduit contains the valve 9 which may be taken as typical of any sort of governing mechanism. The turbine is employed to 35 drive an electric generator 10 which supplies current to any suitable load. The turbine is connected by a conduit 11 with a condenser 12. In order to supply steam to the turbine when the reciprocating engine 40 is not running or is supplying less than is necessary, a boiler 13 is provided, and extending from the dome thereof to the turbine is a pipe containing a regulating valve 14 which may be taken as typical of any 45 suitable form of governing mechanism for regulating the supply of high-pressure steam to the turbine.

In Fig. 2 the turbine is shown in section. The wheel casing 15 is divided by a diaphragm 16 into two parts, each part containing a number of stages, those above the diaphragm being high-pressure stages, and those below, low-pressure stages. The portions of the casing referred to are divided by 55 diaphragms 17 into compartments, each compartment containing a wheel 18 having rows of peripheral buckets adapted to extract the energy of the motive fluid issuing from the admission nozzle 19 and the stage nozzles 20 of the high-pressure portion, and the admission nozzle 21 and the stage nozzles 22 of the low-pressure portion. Under normal conditions the high-pressure stages are cut out and the wheel chambers thereof connected to the 60 condenser by the conduit 23, the valve 24

being in the open position. The exhaust from the reciprocating engine enters the low-pressure portion of the turbine by the conduit 8. The diaphragm 16 between the high- and low-pressure portions of the 70 turbine is by-passed by a conduit 26 containing a valve 27 that is normally closed. When operating under normal conditions, the two upper stages will do no work, the shaft being driven entirely by the low-pressure stages. Assuming, however, that for some reason the supply of exhaust steam from the reciprocating engine falls below a certain point or decreases altogether, the valve 24 is closed, the valve 14 in the supply 80 pipe from the boiler is opened to admit high-pressure fluid, and all of the high pressure will pass through both portions of the turbine. Under the conditions specified, the supply of motive fluid may come entirely 85 from the boiler or it may come partly from the boiler and partly from the reciprocating engine. In the latter case the steam from the separate sources remains unmixed until it flows into the low-pressure portion. When 90 for any reason the pressure in the supply pipe connecting the engine and turbine exceeds a certain amount, a relief valve will open and discharge the excess to the atmosphere or other exhaust.

Mounted on the main shaft is a fly-wheel 95 28 of suitable size, and rotating in a chamber 29 of the turbine casing that is connected to the condenser. As before pointed out, this fly-wheel tends to prevent fluctuations 100 in speed of the main shaft due to any cause.

In event of the turbine being arranged in two portions with live steam supplied to one portion and exhaust steam to the other, one governing mechanism may be used to regulate the admission of both supplies of motive fluid, and further to open and close the conduit to the condenser. It is evident in a construction of this kind that the variations 105 in the delivery of exhaust steam to the turbine can be balanced wholly or in large part by means of a valve mechanism which admits more live steam when the amount of the exhaust decreases, and decreases the amount of live steam when the amount of 110 the exhaust increases.

In accordance with the provisions of the patent statutes, we have described the principle of operation of our invention, together with the apparatus which we now consider to represent the best embodiment thereof; but we desire to have it understood that the apparatus shown is only illustrative, and that the invention can be carried out by other means.

What we claim as new and desire to secure by Letters Patent of the United States, is,—

1. In combination, a high-pressure engine, a turbine receiving the exhaust from the engine and actuated thereby, the said turbine 130

- being divided into high- and low-pressure portions, means for admitting high-pressure fluid to the high-pressure portion of the turbine and exhaust from the engine to the 5 low-pressure turbine, a condenser, and a weight or mass to assist in decreasing the effects due to fluctuation in fluid pressure which rotates in a vacuum due to the condenser.
- 10 2. A turbine comprising high-pressure stages, low-pressure stages, a casing common thereto, a diaphragm between the high- and low-pressure stages, a valve controlled by-pass around the diaphragm, means admitting fluid from a source of supply to a high-pressure stage from which it flows through the machine and a by-pass to the exhaust, and a means admitting a fluctuating low-pressure fluid to a low-pressure stage.
- 15 3. A turbine comprising high- and low-pressure stages, a casing common thereto, a diaphragm between the high- and low-pressure stages, a by-pass around the diaphragm, a means in the by-pass for interrupting communication between the high- and low-pressure stages, a condenser, means for connecting the high-pressure stages with the condenser when they are not receiving motive 25 fluid and a fly-wheel on the shaft of the tur- bine which is subjected to the effects of the condenser for reducing its rotation losses.
4. A turbine comprising a casing, a diaphragm which divides the casing into portions of high and low pressure, a conduit forming a by-pass around the diaphragm 35 and connecting the portions, a valve therein, a device admitting fluid to the high-pressure portion of the turbine, a device admitting fluid to the low-pressure portion thereof, a means for supplying fluid from an intermittent source to the fluid-admitting device of the low-pressure portion of the turbine, a condenser, and a fly-wheel which is subjected to the effects of the condenser for reducing its rotation losses. 45
5. In combination, an electric generator, a turbine connected to and driving the same, a chambered receptacle, a fly-wheel located in the chamber, and a condenser which creates a vacuum in the chamber to decrease 50 rotation losses of the fly wheel.

In witness whereof, we have hereunto set our hands this 30th day of March, 1907.
